UNITED STATES PATENT OFFICE

2,434,327

COLOSTOMY IRRIGATOR

James W. McArdle, Pittsburgh, Pa., assignor to
 Colostom-Ease Inc., Pittsburgh, Pa., a corpora-
 tion of Pennsylvania

Application September 26, 1947, Serial No. 776,284

3 Claims. (Cl. 128—283)

1

This invention relates to a colostomy irrigator. The object of the invention is to provide a colostomy irrigator which is of simple construction, is sanitary in use, and which will retain the irrigating fluid in the colon for any desired period of time before the irrigating fluid and fecal matter are discharged from the colon.

In the accompanying drawings which illustrate a preferred embodiment of my invention,

Figure 1 is a vertical longitudinal section through the colostomy irrigator, parts being shown in elevation;

Figure 2 is a plan view;

Figure 3 is a longitudinal vertical section through the valve;

Figure 4 is a plan view of the valve; and

Figure 5 is a front elevation of the valve.

Referring more particularly to the accompanying drawings, the colostomy irrigator shown is made of a transparent material such as methyl-methacrylate. It may, however, be made of glass or any other suitable material whether transparent or opaque.

The colostomy irrigator comprises a sealing tube 2 having an inner end 3 provided with an outwardly flanged rim 4 which is adapted to be pressed against the body of the user surrounding the colostomy opening. The outer end 3a of the sealing tube is beveled as indicated by the reference numeral 5 and is connected to the upper beveled end of the discharge tube 6. In the embodiment shown, the bevel 5 is at an angle of about 45° and the diameter of the sealing tube 2 and discharge tube 6 are approximately the same.

A valve indicated generally by the reference numeral 7 is slidable in the sealing tube 2. The valve comprises a valve head 8 and a hollow valve stem 9 having a bore 10 adapted to receive a catheter 11 for supplying irrigating fluid. The outer end 12 of the catheter may be connected to a douche bag (not shown) for supplying the irrigating fluid. The inner end 13 of the catheter is provided with openings 14 for introducing the irrigating fluid into the colon. The valve stem 9 is slidable in an opening 15 formed in the wall of the upper end of the discharge tube 6.

The valve head 8 is cylindrical in shape as shown in the drawings so as to conform to the shape of the upper end of the discharge tube 6. Thus, when the valve is moved to its outer position 16 as shown in Figures 1 and 2, the valve head seals the opening 15 and prevents leakage of irrigating fluid. When the valve head is at its inner position 17 as shown in Figures 1 and 2, it confines the irrigating fluid to the space 18 be-

2

tween the body of the user and the valve head 8.

In carrying out a colostomy irrigation, the device is used in the following manner. The catheter 11 is inserted through the hollow valve stem 9 and the outer end 12 is connected to a douche bag containing irrigating fluid. The end 13 of the catheter is inserted into the colostomy opening, the flange 4 is pressed against the body of the user and irrigating fluid is allowed to flow into the colon. During the irrigating period, the valve head 8 is in the position 17 shown in Figures 1 and 2 or in some other position entirely within the sealing tube 2 which confines the irrigating fluid which may leak from the colostomy opening to the sealing tube and prevents any irrigating fluid or fecal matter from discharging into the discharge tube 6. After the irrigation has been completed, the valve is moved so that the valve head assumes the position 16 shown in Figures 1 and 2. In this position the valve head fits snugly against the rear wall of the upper end of the discharge tube and prevents leakage of irrigating fluid through the opening 15 but allows passage of irrigating fluid and fecal matter through the discharge tube into a closet bowl or other receptacle.

In order to facilitate movement of the valve 7 to its different positions, a portion 19 of the valve stem 9 is reduced in thickness to provide a finger grip.

The valve head 8 serves the dual purpose of confining the irrigating fluid in the sealing tube during irrigation and sealing the opening 15 during discharge of the irrigating fluid. The provision of the bevel 5 at the outer end of the sealing tube and at the upper end of the discharge tube facilitates easy manufacture of the device. The cylindrical shape of the valve head 8 allows it to be moved into close contact with the outer wall 40 of the upper end of the discharge tube so as not only to seal the opening 15 against the leakage of irrigating fluid but also to allow irrigating fluid and fecal matter to discharge freely from the sealing tube into the discharge tube.

45 The invention is not limited to the preferred embodiment but may be otherwise embodied within the scope of the following claims.

I claim:

1. A colostomy irrigator, comprising a sealing tube having an inner end adapted to be pressed against the body of a user, a discharge tube connected to the outer end of the sealing tube, and a valve slidable in the sealing tube, said valve having a valve head and a hollow valve stem, the valve stem being slidable in an opening pro-

vided in a wall of the colostomy irrigator opposite the inner end of the sealing tube, the hollow valve stem being adapted to receive a catheter for supplying irrigating fluid, the valve head, when in its inner position, retaining irrigating fluid in the sealing tube, and when in its outer position, sealing the opening in which the valve stem slides but allowing discharge of irrigating fluid and fecal matter through the discharge tube.

2. A colostomy irrigator, comprising a sealing tube having an inner end adapted to be pressed against the body of a user, the outer end of the sealing tube being beveled, a discharge tube having its upper end beveled and connected to the beveled outer end of the sealing tube, and a valve slideable in the sealing tube, said valve having a valve head and a hollow valve stem, the valve stem being slideable in an opening provided in the wall of the upper end of the discharge tube, the hollow valve stem being adapted to receive a catheter for supplying irrigating fluid, the valve head being cylindrical and conforming to the shape of the upper end of the discharge tube, the valve head, when in its inner position, retaining irrigating fluid in the sealing tube, and when in its outer position, sealing the opening in which the valve stem slides but allowing discharge of irrigating fluid and fecal matter through the discharge tube.

3. A colostomy irrigator, comprising a sealing tube having an inner end adapted to be pressed

against the body of a user, the outer end of the sealing tube being beveled at an angle of about 45°, a discharge tube having its upper end beveled at an angle of about 45° and connected to the beveled outer end of the sealing tube, the sealing tube and discharge tube being of substantially the same diameter, and a valve slideable in the sealing tube, said valve having a valve head and a hollow valve stem, the valve stem being slideable in an opening provided in the wall of the upper end of the discharge tube, the hollow valve stem being adapted to receive a catheter for supplying irrigating fluid, the valve head being cylindrical and conforming to the shape of the upper end of the discharge tube, the valve head, when in its inner position, retaining irrigating fluid in the sealing tube, and when in its outer position, sealing the opening in which the valve stem slides but allowing discharge of irrigating fluid and fecal matter through the discharge tube.
